GREETING CARD

Sol D. Cohen, New York, N. Y., assignor to Paper Novelty Manufacturing Co., New York, N. Y., a corporation of New York

Application August 14, 1936, Serial No. 96,013

3 Claims. (Cl. 46—36)

The invention relates to a greeting card and more particularly to the type used for valentine greetings and has for its object to provide a greeting card of this character carrying one or 5 more animated figures. The device comprises a strip of cardboard backing divided by a score line extending vertically throughout its width whereby the two portions of the cardboard may be 10 folded upon themselves, the backing having secured thereto a strip of paper carrying a design and from which extend one or more figures animated by folding and unfolding of the two portions of the cardboard backing. A more particular object of this invention is to provide a construction of such greeting card in which the superimposed paper strip, carrying a design and the figures to be animated, is provided with crease lines so disposed as to induce a movement of the 15 figures extending from the paper strip when the cardboard is folded and unfolded. A still more particular object of the invention is to provide a device of the character described in which of a plurality of figures one is bent forwardly of the superimposed strip and the other moves in a 20 plane substantially parallel to the backing strip, and upon the folding together of the two portions of the backing strip, disappears behind the superimposed paper strip.

A greeting card constructed in accordance with 30 my invention is thus especially adapted for providing animated figures going through certain motions upon the unfolding of the two portions of the greeting card, such animated figures being entirely enclosed within the peripheral edges of 35 the card when the latter is in closed position but extending beyond such peripheral edges, by the movement thereof induced by a novel system of creases producing an animation in the figures, upon the unfolding of the card to bring the two 40 parts thereof into a position in which they are substantially in a plane.

In the accompanying drawing, in which a particular embodiment of my invention is illustrated, Fig. 1 is a plan view of a greeting card constructed 45 in accordance with my invention in its closed or folded condition; Fig. 2 is a plan view of the device in partly open or partly unfolded condition, illustrating the manner and spheres of movement of the animated figures; Fig. 3 is an edge view of the greeting card in the condition thereof illustrated in Fig. 2; and Fig. 4 is a face view of the greeting card in fully open or unfolded condition.

Referring more particularly to the drawing, 50 in which similar reference characters identify

similar parts in the several views, my novel greeting card comprises two portions 5 and 6 of cardboard formed from a single strip of material and adapted to be folded one upon the other along a crease line 7 extending throughout the width of 5 the strip substantially intermediate the two ends thereof.

Secured to the cardboard strip constituted of the portions 5 and 6, by suitable adhesive, is a strip of paper 8 of much thinner gauge than 10 the cardboard backing, such strip of paper, carrying any desired design, for instance, in the particular embodiment illustrated, the representation of a stone wall, having its end portions 9 and 10 secured to the cardboard backing. The 15 right-hand edge 11 of the portion 9 is preferably disposed at a distance from the crease line 7 which is substantially the same as the width of the portion 12, the portion 13 extending from the edge 11 of panel 9 to the edge 14 of the panel 20 12. The edge 14 constitutes a fold line extending vertically of the superimposed paper strip to a point 15, the crease continuing from such point at a slight angle from the vertical so as to form the crease line 16. From the point 15, constituting the juncture of crease lines 14 and 16, extend two additional crease lines 17 and 18 forming acute angles with the crease line 16. A figure 19, in the particular embodiment of the invention illustrated in the drawing, the figure of 30 a boy, extends upwardly as a projecting portion integral with the superimposed paper strip.

The edge 11 of the panel 9 comprises a crease line which has an extension 20, which extension, however, is slightly at an angle to the vertical 35 and is disposed in approximately the same direction as the crease line 16. From the point of juncture 21 of the crease lines 11 and 20 two crease lines 22 and 23 extend upwardly and outwardly. A figure 24 constitutes an extension of 40 the portions of the superimposed paper strip above the crease lines 22 and 23.

The crease lines 17 and 18 are such that the material on each side of such crease lines when 45 the two portions of the backing strip are being brought toward each other in the operation of folding the greeting card, form a dihedral angle facing toward the backing sheet, whereas the crease line 16 is such that the two strips of material on each side thereof form, when the card 50 is being folded, a dihedral angle, facing away from the backing sheet. The surfaces between the two crease lines and the extending crease line constitute a pair of triangles which form, when the card is partly unfolded, a dihedral angle fac- 55

ing toward the backing sheet in the case of one of the animated figures, and in the case of the other animated figure away from the backing sheet, the apices of the triangles meeting at a common point, with the extending crease line constituting the edge of such dihedral angle, and extending, in such partly unfolded condition of the card, from the apices of the triangles toward the backing sheet in one of the animated figures, and away from the backing sheet in the case of the other animated figure. This construction produces an animation of the figure 19 such that as the two portions 5 and 6 of the greeting card are being folded, one upon the other, the figure 15 19 moves downwardly in a plane substantially parallel to the plane of the greeting card so as to disappear behind the superimposed strip. The construction, producing animation of the figure 24, is such that as the two portions of the backing sheet are being folded, the figure 24 is moved first forwardly of the superimposed paper strip and then sidewise so as to be folded over, but in front of, the body of the superimposed strip.

It will be noted that in my novel greeting card 25 the panel 9 of the superimposed paper strip is secured to the cardboard backing in such position that the vertical crease line 11 is spaced from the score line 7 approximately the same distance as the width of the panel 12 near the other end of the superimposed strip. This spacing of the crease line 11 from the score line 7 spaces the large panel of the strip 13 from the backing strip as the greeting card is being folded or unfolded so that the animated Figure 19 is accommodated in such space between the cardboard backing and the superimposed strip when the two portions of the cardboard strip are folded.

Of course, it is obvious that only a single animated figure may be provided on the superimposed paper strip and that such figure may be either that represented by the figure 19 or that represented by the figure 24. It is also obvious that the particular design imparted to the superimposed paper strip and the figures extending therefrom are merely illustrative. Specific changes may therefore be made either in the configuration of the several parts constituting my novel greeting card or in their disposition without departing from my invention.

I claim:

1. A greeting card of the class described comprising a strip of cardboard divided by a score line extending vertically throughout its width, a strip of paper carrying a design and secured to said cardboard and a figure integral with said strip and extending therefrom, adapted to be animated by folding and unfolding the two portions of the cardboard strip, such animation consisting of the movement in a plane substantially parallel to the cardboard strip of such figure so as to disappear behind said superimposed paper strip upon the folding of the two portions of such cardboard strip. 5

2. A greeting card of the class described comprising a strip of cardboard divided by a score line extending vertically throughout its width, a strip of paper carrying a design and secured to said cardboard and a plurality of figures integral with said strip and extending therefrom, adapted to be animated by folding and unfolding the two portions of the cardboard strip, such animation consisting of the bending forwardly of the superimposed strip of one of such figures and the movement in a plane substantially parallel to 15 the cardboard strip of the other of such figures so as to disappear behind said superimposed paper strip upon the folding of the two portions of such cardboard strip. 20

3. A greeting card of the class described, comprising a cardboard backing having two portions divided by a score line extending vertically substantially intermediate the length of the cardboard backing, a superimposed paper strip secured at its end portions to said backing and 30 having its major portion spaced from said backing when the card is partly folded, said paper strip being provided near one end thereof with a vertical crease line, a crease line forming an extension upwardly of said first mentioned crease 40 line but disposed at an angle to the vertical, and two crease lines extending upwardly from the point of juncture of said first mentioned crease lines at acute angles from said extending crease line, the surfaces between said two crease lines 45 and the extending crease line being at an angle to one another and forming, when the card is partly unfolded, a dihedral angle. 35
